(57) **CLAIM**

The ornamental design for a wearable sensor docking station as shown and described.

DESCRIPTION

FIG. 1 is a perspective view of a wearable sensor docking station, showing our new design;

FIG. 2 is a front view of the wearable sensor docking station;

FIG. 3 is a rear view of the wearable sensor docking station;

FIG. 4 is a left side view of the wearable sensor docking station;

FIG. 5 is a right side view of the wearable sensor docking station;

FIG. 6 is a top view of the wearable sensor docking station; and,

FIG. 7 is a bottom view of the wearable sensor docking station.

The broken lines shown represent unclaimed subject matter and form no part of the claimed design. The shade lines shown represent surface shading and not surface ornamentation, color, or material type. The long-dash short-dash lines show an unclaimed boundary that forms no part of the claimed design. The space between the long-dash short-dash lines and broken lines also forms no part of the claimed design.

1 Claim, 7 Drawing Sheets
